SECTIONAL BRUSH

Edward J. Goeritz, Arlington, Minn.

Application February 14, 1934, Serial No. 711,270

5 Claims. (Cl. 15—202)

This invention relates to an improved hair-brush for professional and home use wherein the brush is made up of separable sections allowing the sections to be separated for washing and cleaning purposes.

The principal novelty is predicated upon the sectional construction of the head of the brush, this being such as to match the bristles of the respective sections in such intimate and coordinating manner as to provide a bristle assembly having all the advantages of the regular one-piece or solid type brush, but having the additional advantage of permitting the sections and the bristles carried thereby to be disconnected for convenient scraping and cleansing.

Briefly stated there is a main section which includes a head or back wherein this is slotted to form a group of companion bristle carrying members, together with a complementary or secondary section constructed so as to form the complete head and including furcations or bristle carrying members cooperating with the first named members in defining the finished or complete brush head.

One feature of the improved construction resides in the adoption and use of a practicable and conveniently located resilient latch carried by the relatively movable or secondary section which serves as a fastener for connecting the two sections securely together in an expeditious and dependable manner.

A further feature of the invention is predicated upon a brush head composed of complementary sections with their portions or bristle carrying members interlocked wherein the two sections are provided with dowel or locking pins cooperating with retaining sockets in such a manner as to keep the two sections in an even plane and to thereby dispose the bunches of bristles in substantially flush relationship.

Other features and advantages will become more readily apparent from the following description and drawings.

In the drawings:

Figure 1 is a top plan view of the complete brush showing the two sections assembled and illustrating the manner in which the latch or fastener operates in keeping said sections together in a positive manner.

Figure 2 is an edge elevational view of the structure illustrated in Figure 1.

Figure 3 is a bottom plan view of Figures 1 and 2.

Figure 4 is a bottom plan view of the handle equipped or main section of the brush head.

Figure 5 is a corresponding view of the complementary or secondary section, this being the latch carrying section.

Figures 6 and 7 are longitudinal and transverse sectional views taken on the planes of the lines 6—6 and 7—7 respectively of Figure 1.

Figure 8 is a cross section on the line 8—8 of Figure 5, and

Figure 9 is a detail horizontal section on the plane of the line 9—9 of Figure 2.

Briefly stated it will be observed that the two sections carrying the bristles and constituting the complete head are dovetailed together, that is the bristle carrying members thereof are interlocked and fastened through the instrumentality of dowel pins and held assembled by a manually releasable retaining latch.

Referring now to the preferred embodiment of the invention illustrated in the drawings it will be seen that the main or handle equipped section of the brush shown in Figure 4 comprises a head forming section 10 having an integral handle 11. The portion 12, sometimes referred to as the back, and sometimes as a head, is of rectangular or longitudinally elongated configuration. In the present instance it is formed with a pair of spaced parallel longitudinally extending slots which define a group of three like bristle carrying members 13. These carry rows of aligned bunches of bristles differentiated by the numerals 14. Then there is a transverse row of bristles adjacent the junction of the head and handle which are distinguished by the numerals 15, these being end bristles. At their free end the bristle carrying members 13 are provided with pegs or dowel pins 16. These are adapted to fit in coordinating sockets 17 formed in the segmental block like portion 18 of the relatively movable detachable brush section 19 (see Figure 5). Incidentally the sockets are shown better in Figure 8 and the cooperation between the pins and sockets is shown in Figure 9. It is to be pointed out however that the pair of bristle carrying members 20 of the section 19 are provided with similar dowel pins 21 which extend in the sockets provided in the head 12 and this alternate arrangement of dowel pin connections keeps the two sections 10 and 19 in proper alignment, that is in a plane even with each other. The segmental configuration of the connecting block 18 provides the desired finish or end formation for the brush making it of the general appearance of an ordinary one-piece or solid head construction. This block 18 carries a row of bristles 22 and the members 20 also carry

bristles 23 all of these bristles cooperating in forming the complete bristle assembly designed to provide the desired smooth and uniform brushing action.

- 5 To prevent relative longitudinal sliding movement of the two sections of the brush head I have found it expedient and satisfactory to provide a connecting latch. This latch is shown in Figure 1 and denoted by the numerals 24 and is of general Y-shaped form. The diverging arm portions 25 are pinned or otherwise secured as at 26 to the free ends of the bristle carrying members 20. The stem portion 27 overlies the inner end of the main brush head section 12 and has its free 15 end fashioned into a clip. In other words it is bent down upon itself to form a cam-like keeper 28 of the type shown in Figure 6 and this cooperates with the undercut or beveled retaining shoulder 29 in a keeper seat or recess 30 formed in 20 the handle. The up-bent portion of the metal has its extremity bent laterally as at 31 in a plane above the handle so as to form a convenient finger piece or grip to facilitate disengagement of the keeper 28 from the shoulder 29. It is obvious 25 that by simply sliding the two sections together and interlocking the bristle carrying members the keeper portion of the latch will snap automatically into the recess 30 in a practical and dependable manner. It can be just as easily disengaged and the two sections then pulled apart so that the meeting portions or contacting parts thereof can be scraped and cleaned, sterilized and then allowed to dry and then again assembled for complete brush formation.
- 30 A head constructed in accordance with the principles of the present inventive conception is simple, economical, efficient and promotes requisite sanitation desired by the individual home user, the barber, or the professional hair dresser.
- 35 It possesses the requisite commercial appeal such as would merit endorsement by the trade when used in public because of its sanitation features.
- It is thought that persons skilled in the art to which the invention relates will be able to obtain a clear understanding of the invention after 40 considering the description in connection with the drawings. Therefore, a more lengthy description is regarded as unnecessary.
- 45 Minor changes in shape, size, and rearrangement of details coming within the field of invention claimed may be resorted to in actual practice, if desired.
- 50 Having thus described my invention, what I claim as new is:
- 55 1. A hairbrush of the class described comprising a bristle equipped head, said head embodying a pair of complemental head forming sections including longitudinal and extending spaced parallel bristle carrying members disposed in interlocking relationship, dowel pins carried by the respective sections and receivable removably in sockets in adjacent portions, together with a

5 latch carried by one section, said latch being formed with a keeper element, and the remaining section having a keeper seat for reception of said element.

2. A hairbrush of the class described comprising a head, said head embodying separably connected complemental bristle equipped sections, one section being provided with a keeper notch having an undercut retaining shoulder, the other section being provided with a substantially Y-shaped resilient latch having its stem portion terminating in a down bent cam like keeper releasably engageable with said shoulder.

3. A hairbrush of the class described comprising a head, said head embodying separably connected complemental bristle equipped sections, one section being provided with a keeper notch having an undercut retaining shoulder, the other section being provided with a substantially Y-shaped resilient latch having its stem portion terminating in a down bent cam like keeper releasably engageable with said shoulder, and further formed with an upstanding portion terminating in a laterally bent finger piece disposed in a plane above said handle.

4. A brush of the class described comprising a handle having an integral longitudinally elongated head forming section of a flat faced type, said head section being longitudinally cut to define a group of spaced parallel members, bristles 30 carried by and depending from said members, said members being provided at their outer end with connecting pins, a complemental brush head section fashioned for cooperation with said first named section and including a block like end 35 portion formed with spaced parallel bristle carrying members, said last named members being interlocked between the corresponding members of the first named section and formed with connecting pins.

40 5. A brush of the class described comprising a handle having an integral longitudinally elongated head forming section of a flat faced type, said head section being longitudinally cut to define a group of spaced parallel members, bristles 45 carried by and depending from said members, said members being provided at their outer end with connecting pins, a complemental brush head section fashioned for cooperation with said first named section and including a block like end portion formed with spaced parallel bristle carrying members, said last named members being interlocked between the corresponding members of the first named section and formed with connecting pins, a substantially Y-shaped latch, the arm of 55 the Y being fastened to the free end of the bristle carrying members of the second named brush head section, said handle having a keeper notch formed therein, and the stem portion of said latch being formed with a laterally bent keeper 60 receivable in said recess in the manner described.

EDWARD J. GOERITZ.
